DRUM SNARE ADJUSTER

Cecil H. Strupe, Indianapolis, Ind.

Original application June 14, 1934, Serial No. 730,616. Divided and this application August 8, 1935, Serial No. 35,249

16 Claims. (Cl. 84—415)

5 My invention relates to improvements in drums and has for one of its objects that of providing means by which the snares of a snare-drum may be individually tensioned and unitarily moved to and from effective position.

Another object of my invention is to provide improved means for moving the snares of a drum to an effective position and to provide means for adjusting the tension of all of the snares simultaneously.

Other objects and advantages of my invention will appear more fully hereinafter in the accompanying specifications and claims.

15 For the purpose of disclosing my invention, I have illustrated certain embodiments thereof in the accompanying drawings in which

Fig. 1 is a fragmentary section of a snare mechanism embodying my invention.

20 Fig. 2 is an elevation of one end of the snare mechanism illustrated in Fig. 1.

Fig. 3 is a fragmentary side elevation partly in section showing a modified form of the snare mechanism.

25 Fig. 4 is an end view of one of the snare holders illustrated in Fig. 3.

Fig. 5 is an end view of the opposite snare holder embodying the structure illustrated in Fig. 3.

Fig. 6 is a sectional view on the line 6—6 of Fig. 4.

30 Fig. 7 is a sectional view on the line 7—7 of Fig. 5.

Fig. 8 is a side elevation of another embodiment of my invention.

Fig. 9 is an end view thereof.

35 Fig. 10 is a view similar to Fig. 8 except that certain of the parts are shown in section.

Fig. 11 is a side elevation of the opposite snare holder for use in connection with the structure illustrated in Fig. 8 or other of the structures illustrated.

Fig. 12 is an end elevation of the structure shown in Fig. 11; and

Fig. 13 is a sectional view of the structure illustrated in Fig. 11.

40 In the structure illustrated, the usual open ended cylindrical shell 1 of the drum is provided with the usual head rings 2, the associated heads 3 and the associated straining rings 4. The heads may be adjusted as to tension by any suitable adjusting mechanism as for instance, that illustrated in my copending application filed June 14, 1934 Serial No. 730,616 for drums of which, so far as it pertains to the common subject matter disclosed therein, this present application is a division.

Secured to the outside of the shell 1 at diametrically opposite points are two posts 5 to each of which is pivoted a U-shaped link 6 to which is pivoted the bifurcated upper end of the arm 7 provided with a downwardly presented heel 8 and a crossbar 9 laterally spaced from the heel. Detachably secured to the heel 8 of the crossarm is a perforated plate 10 through which the snares 11 are strung and both ends of these snares are carried over the adjacent crossbar 9 and projected through the adjacent straining ring and across the drum head again through the straining ring and over the crossbar 9 of the other arm 7 to the adjacent heel 8 upon which the ends of the snares are clamped by a bar 12 through which the clamping screws 13 are projected into the heel. In this arm 7, above its heel 8, there are pivoted a number of triangular levers 14 corresponding in number and registering with the several snares, one arm of each lever being engageable with a snare. The other arms of the levers are engaged respectively by temper screws 15 which are threaded through this arm 7 above the heel so that the snares may be individually strained by proper adjustment of the lever 14. 20 25

Secured to the inside of the shell 1 in radial alignment with the arms 7 are brackets 16 in each of which is pivoted a bell crank lever 17 provided at the ends of its two arms with trunnion nuts 18 and 19. Each nut 18 receives the 30 threaded portion of a screw 20 which is projected through the adjacent arm 7 and through the shell 1 and provided at its outer end with a knurled nut, by means of which it may be readily manipulated. The two nuts 19 are connected 35 together by a stretcher rod 21 and the two bell crank levers are reversely set in their respective brackets with their arms which carry the nuts 18 approximately parallel with the adjacent drum head when said levers are in their medial position. 40

Attached to one of the links 6 so as to form an operative arm therefor is a finger 22 which is projected upwardly to a point somewhat above the plane of the upper drum head. 45

By swinging the upper end of the finger 22 outwardly, the link 6, to which it is attached, is swung downwardly, thereby lowering the arm 7 which depends therefrom, and the movement of this arm through the medium of its screw 20, 50 swings the adjacent bell crank lever which, through the medium of the stretcher rod, swings the other bell crank lever which, through the medium of its nut 18 and associated screw 20, 55 causes the other depending arm 7 to move down-

wardly so that the snares are moved away from the adjacent drum head and in substantial parallelism therewith. Movement of the finger 22 back to the position shown in the drawings brings the snares in parallelism up against the adjacent drum head.

As shown in Fig. 1 the nuts 19 pass across the dead centers of the bell crank levers as the arms 7 pass from upper to lower position or vice versa so that the tension in the snares acts to hold the parts in either extreme.

It will be noted that one arm of each bell crank lever 17 projects from the pivotal anchorage of the lever toward the adjacent snare carrying arm 7, and this arm or lever 17 is so arranged that its outer end crosses a plane through the lever axis and parallel with the drum head so that each of the said bell crank arms, in conjunction with the strut screw 20, forms a sort of 20 toggle, the knuckle of which is carried over an intermediate dead center as the snares are shifted to or away from the drum head. As a result of this arrangement, the tension of the snares acts to yieldingly hold the snares in either extreme of lateral adjustment.

It will, of course, be apparent that if desired, lateral snare movement can be provided at one end in which case the range of movement should be somewhat greater. It also will be noted that 30 by the manipulation of the strut screw, arms 7 may be swung to and from the shell 1 on their pivots on the arm 6 and thereby adjust the tension of the snares as a whole.

In Figs. 3 to 7 inclusive I have shown, in modified form, a snare mechanism. In this structure a U-shaped bracket 24 is secured to the side of the drum near the bottom, the two arms 25 of which extend substantially at right angles to the shell. A snare clamp 26 is pivotally connected to these arms through the instrumentality of links 27 pivoted to the sides of the clamp and to the end of the arm. This clamp is somewhat V-shaped with the base of the V extending toward the bottom of the drum and is provided with a 40 pair of downwardly extending arms 28 between which is swivelly mounted one snare clamping member 29. The other snare clamping member 30 is adapted to be connected to the first member by means of tightening screws 31 and between 45 these members is inserted a soft metal-bearing member 32. Also mounted on the shell is a post 33 on which is swingably or pivotally mounted a bell crank lever, the longer arm 34 of which provides a finger mechanism for tightening or releasing 50 the snares by vertically moving the snare clamp 26. The shorter arm 35 of this lever is connected to a vertically movable arm 36 by a pivoted link 37 and this vertically movable arm has the clamp 26 pivoted thereto by the same pivot pins 38 that 55 connect the links 27 to the snare clamp. By this arrangement, the snare clamp may be vertically moved and at the same time the clamp is rockably mounted relatively to the shell. For adjusting this rocking movement, I provide a set screw 39, threaded into the arm 36 and having a head 40 bearing on the upper end of the snare clamp. In order to guide the vertically movable member 36, this member is slotted as at 41 to take the pivot pin of the lever 35.

Mounted on the shell diametrically opposite the snare clamp 26 is another snare clamp, comprising a pair of arms 42 connected together by integral cross bar 43, which arms are pivoted as at 44 to the T head 45 of a supporting bracket 46 mounted on the drum shell. These arms 42

have secured between them at their lower ends a clamp similar to the clamp comprising the members 29 and 30 for gripping the snares. This snare clamp extends at an angle outwardly and inwardly toward the shell and is biased to swing 5 toward a vertical position by a coiled spring 47 fitting in a recess in the bracket 46. It is, therefore, apparent that due to the angular disposition of this clamping member, when the snare clamp 26 is lowered, the tension on the snares 10 will be somewhat relieved and under the influence of the spring 47 the snares at their opposite ends will also be lowered. Furthermore, it is to be noted that by the swinging of the snare clamp on its pivot 38 to move the lower end of the snare clamp in or out, a corresponding movement will 15 take place with the opposite clamp.

In Figs. 8 to 10 inclusive, I have illustrated a still further modification of my snare mechanism for one side of the drum. Referring to the 20 structure shown in these figures, a U-shaped bracket 48 is secured to the side of the drum shell and between the two arms 49 of this bracket is pivoted a lever 50 provided with a finger manipulator 51. A second bracket 52 is secured to the 25 side of the drum shell at a point slightly below the bracket 48 and a pair of links 53 are pivotally connected to this bracket extending substantially in parallelism with the link or lever 50. These links 53, at their outer ends, have secured between the same a nut 54 through which passes an adjusting screw 55. This adjusting screw provides a mounting for the snare clamp arm 56 which at its lower end is pivotally connected as at 57 to the lever 50. The screw 55 is provided with a knurled adjusting head 58 which receives between it and a collar 59 on the screw a portion 60 of the arm 56. The upper end of the arm is provided with a flattened cross bar 61 on which is clamped a clamping bar 62, clamping bolts 63 40 being provided for securing the bar 62 in position and this bar providing means for securing to the arm 56 one end of the snares.

At a diametrically opposite point on the drum shell I provide a second snare holder somewhat 45 similar to the structure illustrated in Figs. 5 and 7. In the structure illustrated in Figs. 11, 12, and 13, however, I have provided a bracket 64 which is secured to the side of the shell by suitable bolts or screws 65 and connected to this bracket is a U-shaped bracket 67 by means of the bolt 66 and to the outer ends of this U-shaped bracket 67 is mounted a rocking arm 68 which is pivoted to the arms of the bracket 67 by pivoting rod 69. A tail piece 70 extends upwardly from the arm 68 55 and the lower end of this tail piece is slotted to receive the end of a rod or bolt 71, the outer end of which extends through an opening 72 in an extension 73 of the bracket 67. And between the teat 74 of the arm 73 and a collar 75 on the bolt 71 is interposed a coiled spring which maintains the U-shaped member 68 biased in a direction to strain the snares. The opposite ends of the snares are clamped between a cross bar 76 60 carried between the arms of the member 68 and a clamping bar 77.

It is apparent that when the lever 50 is manipulated through the instrumentality of the finger piece 51, the arm 56 will be raised or lowered and, due to the peculiar movement of this arm which, as a matter of fact, rocks on the nut 54 as well as moves vertically on the links 53 and the lever 50, the member 68 will also rock on its pivot 69 and move the opposite ends of the snares toward and 70 away from the drum head.

I claim as my invention:

1. In a snare drum, the combination with a main shell and a head associated therewith, of snares projected across said head, an anchorage for the snares at one side of said shell, an anchorage at the opposite side of said head for said snares comprising a depending arm substantially parallel with said shell having snare-holding means at one end, a link pivotally mounted on said shell and pivotally associated with said arm, and a tension screw anchored on said shell and arm for adjusting the snare-holding end of said arm toward and from said shell.
2. In a snare drum, the combination with a main shell and a head associated therewith, of snares projected across said head, an anchorage for the snares at one side of said shell, an anchorage at the opposite side of said head for said snares comprising a depending arm having snare-holding means at one end, a link hinged on said shell on an axis transverse to the axis of the shell and pivotally associated with said arm, and a lever for moving said arm to throw said link past its dead center in either direction.
3. In a snare drum, the combination with a main shell and a head associated therewith, of snares projected across said head, an anchorage for the snares at one side of said shell, an anchorage at the opposite side of said head for said snares comprising a depending arm having snare-holding means at one end, a link hinged on said shell on an axis transverse to the axis of the shell and pivotally associated with said arm, a lever for moving said arm to throw said link past its dead center in either direction, and a tensioning screw anchored on said shell and arm for adjusting the snare-holding end of said arm toward and from the shell.
4. In a snare drum, the combination with a main shell and a head associated therewith, of snares projected across said head, an arm pivotally mounted on one side of said shell and having means for holding the snares at one end, an anchorage at the opposite side of said shell comprising a depending arm having snare holding means at one end, a link hinged on said shell on an axis transverse to the axis of said shell and pivotally associated with said arm, means for moving said arm to throw said link past its dead center in either direction, and means for causing the opposite arm to move coincidentally with said last mentioned arm whereby the snares will be moved to and from the head in parallelism with the head.
5. In a snare drum, the combination with a main shell and a head associated therewith, of snares projected across said head, an anchorage for the snares at one side of said shell, an anchorage for the snares at the opposite side of said head comprising a depending arm supported on said shell having snare-holding means at one end, a lever operatively connected to the shell and arm for causing said arm to move in a direction to move said snares to and from the head, and means for moving the lower end of said arm to and from the shell with said first mentioned movement.
6. In a snare drum, the combination with a main shell and a head associated therewith, of snares projected across said head, an anchorage for the snares at one side of said shell comprising an arm pivotally mounted on said shell on an axis transverse to the axis of said shell and inclined towards said shell, means for biasing said arm to rock downwardly to move said snares away from said head, an anchorage for the snares at the op-

posite side of said shell comprising a depending arm having snare-holding means at one end, a link hinged on said shell on an axis transverse to the axis of the shell and a lever for moving said arm and link in a direction to move the snares to and from the drum head and the lower end of said arm to and from the drum shell.

7. In a snare drum, the combination with a main shell and a head associated therewith, of snares projected across said head, an anchorage for the snares at one side of said shell, an anchorage at the opposite side of said head for said snares comprising a depending arm having snare-holding means at one end, a link hinged on said shell on an axis transverse to the axis of the shell and pivotally associated with said arm, and a tension screw anchored to said link and said arm for adjusting the snare-holding end of said arm toward and from the shell.

8. In a snare drum, the combination with a main shell and a head associated therewith, of snares projected across said head, an anchorage for said snares at one side of said shell, an anchorage on the opposite side of said shell for said snares comprising a depending arm having snare-holding means at one end, a bell crank lever hinged on said shell on an axis transverse to the axis of the shell and pivotally connected to the upper end of said arm, and a link hingedly mounted on said shell on an axis transverse to the axis of the shell and pivotally associated with said arm at a point intermediate of its ends.

9. In a snare drum, the combination with the main shell thereof, of two diametrically opposed links pivoted on the shell on axes at right angles to the axis of the shell, two arms substantially paralleling the drum shell and pivotally connected with the adjacent link, snares extended between and connected to the free ends of said arms, two bell crank levers pivoted within the shell, a stretcher rod connecting said bell crank levers, and laterally projecting elements carried by said arms and projected through the drum shell into association respectively with the adjacent bell crank lever.

10. In a snare drum, the combination with the main shell thereof, of two diametrically opposed links pivoted on the shell on axes at right angles to the axis of the shell, two arms substantially paralleling the drum shell and pivotally connected with the adjacent link, snares extended between and connected to the free ends of said arms, two bell crank levers pivoted within the shell, a stretcher rod connecting said bell crank levers, and laterally projecting elements carried by said arms and projected through the drum shell operatively connected respectively with the said bell crank levers, one of said projecting elements being adjustable as to effective length.

11. In a snare drum, a snare anchorage comprising an arm having means for clamping the ends of a plurality of snares, a plurality of levers, one associated with each snare, and a corresponding plurality of adjusting screws, each cooperating with a lever to move the same to laterally stress, and thereby longitudinally tension, the snare with which it is associated.

12. In a snare drum, the combination with the main shell and a head associated therewith, of a snare anchorage arranged at one side of the main shell with snares anchored at one end thereon and extended across the head, an arm arranged alongside the shell at the opposite side and engaging the adjacent ends of the snares, a link hinged on the shell on an axis transverse to the shell

axis, a hinge connection between said link and said arm, a second arm pivotally anchored at one end on the shell with its other end projecting toward the first-mentioned arm and a variable-length strut interposed between said two arms, and so connected to the arms that, as the first-mentioned arm is shifted transversely of the head from one extreme to the other the unanchored end of the second arm will pass from one side to the other of a line passing through the anchorage of the second arm and parallel with the drum head.

13. In a snare drum, the combination with the main shell and a head associated therewith, of a snare anchorage arranged at one side of the main shell with snares anchored at one end thereon and extended across the head, an arm arranged alongside the shell at the opposite side and engaging the adjacent ends of the snares, a link hinged on the shell on an axis transverse to the axis of the shell, a hinge connection between said link and said arm, a second arm pivotally anchored at one end on the shell with its other end projecting toward the first-mentioned arm and a strut interposed between said two arms, and so connected to the arms that, as the first-mentioned arm is shifted transversely of the head from one extreme to the other the unanchored end of the second arm will pass from one side to the other of a line passing through the anchorage of the second arm and parallel with the drum head.

14. In a snare drum, the combination with the main shell and head, of snares extending across the head, an anchorage for one end of said snares, an anchor member for the other end of said snares movable axially of the shell to move the snares to and away from contact with the head, an arm pivotally anchored on the shell on an axis transverse to the axis of the shell, and a variable-length strut interposed between said movable

anchor member and the outer end of said arm, the strut and arm being so connected that movement of said anchor member from its one extreme to the other will move the connection between the pivoted arm and said strut across the plane of the pivotal anchorage parallel with the head and the tension of the snares will act to yieldingly retain the arm in either extreme.

15. In a snare drum, the combination with the main shell and head, of snares extending across the head, an anchorage for one end of said snares, an anchor member for the other end of said snares movable axially of the shell to move the snares to and away from contact with the head, an arm pivotally anchored on the shell transverse to the axis of said shell, and a strut interposed between said movable anchor member and the outer end of said arm, the strut and arm being so connected that movement of said anchor member from its one extreme to the other will move the connection between the pivoted arm and said strut across the plane of the pivotal anchorage parallel with the head and the tension of the snares will act to yieldingly retain the arm in either extreme.

16. In a snare drum the combination with the main shell thereof, of a snare clamp, a carrier for said clamp pivotally carried at its upper end by the shell and carrying the clamp at its lower end, said clamp being inclined downwardly and inwardly towards the shell and a spring interposed between the free end of said arm and a stationary part on the shell biasing said clamp towards a position parallel with the shell, a second snare clamp mounted on the opposite side of said shell, a vertically-movable link mounted on said shell and said clamp being pivotally movable on the link to pivot at right angles to the shell and lever means for vertically moving said link.

CECIL H. STRUPE.
